(57) **CLAIM**

The ornamental design for a speculum with transversely oriented position retaining arrangement, as shown and described.

DESCRIPTION

FIG. 1 is a top plan view of a speculum with transversely oriented position retaining arrangement;

FIG. 2 is a front elevational view thereof;

FIG. 3 is a right side elevational view thereof;

FIG. 4 is a left side elevational view thereof;

FIG. 5 is a bottom plan view thereof;

FIG. 6 is a rear elevational view thereof;

FIG. 7 is a top plan view of a second embodiment of the speculum as disclosed in FIG. 1;

FIG. 8 is a front elevational view thereof;

FIG. 9 is a right side elevational view thereof;

FIG. 10 is a left side elevational view thereof;

FIG. 11 is a bottom plan view thereof; and,

FIG. 12 is a rear elevational view thereof.

The broken lines in FIG. 5 adjacent to the claimed areas represent the bounds of the claimed design and are for illustrative purposes only; the broken lines form no part of the claimed design.
